HAIRPIN

Raymond Larson, Chicago, Ill.

Application September 5, 1939, Serial No. 293,481

7 Claims. (Cl. 132—56)

This invention relates to new and useful improvements in hairpins.

Among the objects of my invention is to provide an improved hairpin having a novel surface whereby the retainment of such hairpin in its position in the hair is facilitated by the resistance to displacement of the texture or finish of such surface and whereby the luster or color of such surface tends to harmonize with the sheen and color of the hair thus imparting to such hairpin the quality of invisibility.

It is also an object of my invention to improve the construction of the hairpin by providing the intermediate looped portion with a flattened or thinned central section to cause such flattened section to extend outwardly of the adjacent side portions of the loop to facilitate the manual withdrawal of the hairpin from the hair.

I am aware of the existence of hairpins which are coated with baked colored compositions to provide light diffusion and which compositions are of such type that in drying a somewhat roughened surface is provided which is intended to resist the displacement of such hairpin, but I have found that none of these coatings actually did provide the desired resistance to displacement because the irregular undulations, grooves or fissures formed in the surface of such coatings were of comparatively large elongated irregular curves and lines and smooth faces, when compared to the size of a single hair, and therefore did not provide the necessary texture for the desired resistance to displacement.

Others have attempted to produce the desired displacement-resisting surface of such hairpins by mechanically roughening or rolling the metal stock to provide closely arranged angular faces, grooves or corrugations but such mechanical treating did not provide the desired resistance because such grooves or corrugations were still comparatively too large and smooth in texture and not sufficiently irregular.

The structural texture of the surface of my improved hairpin provides the desired resistance to displacement of such hairpin because such surface consists of exceedingly fine, preferably microscopic and very irregular, metallic particles or bronzes supported on the stock of the hairpin in pigmented lacquers, enamels or suitable colored liquid vehicles preferably of the quick drying type, the minute size, irregularity and color of such closely disposed metallic particles producing a surface texture of the desired frictional resistance and at the same time afford-

ing the desired luster and color to harmonize with the sheen of the hair.

It is therefore, an object of my invention to provide a hairpin of improved construction, color and surface texture whereby its practicability is substantially enhanced by facilitating its manual withdrawal, by increasing its resistance to undesired displacement, and by reducing its degree of visibility through its color harmony with the color of the hair.

A preferred embodiment of my invention is illustrated in the attached drawing, wherein

Fig. 1 is a plan view of the hairpin;

Fig. 2 is a side view of same;

Fig. 3 is a plan view of the hairpin before the pin has been crimped and bent into the desired shape as shown in Figs. 1 and 2;

Fig. 4 is a side view of the pin in the form shown in Fig. 3;

Fig. 5 is an enlarged cross-section taken on line 5—5 of Fig. 4 showing the flattened medial portion;

Fig. 6 is a greatly enlarged perspective view of an end portion of the pin stock coated in accordance with my invention;

Figs. 7 and 8 are enlarged diagrammatic cross-sections of respectively a human hair and one of the irregular metallic particles used in my improved coating, and

Fig. 9 is an enlarged elevational view of a portion of a hairpin metal stock twisted along its longitudinal axis to produce the improved surface finish.

As shown in the illustrations, 10 indicates a flat thin hairpin stock preferably of metal; however, it will be readily apparent that my invention is adapted for embodiment in hairpin stocks of other materials and cross-sections, and in hairpins or bob pins of other shapes and designs.

The strip of flat material 10 is mechanically flattened intermediate its ends, as at 11, to provide a comparatively wider, arcuate and thinned portion in the medial part of the loop as shown in Figs. 1 and 2. The purpose of such flattened medial loop portion 11 is to provide a wider and thinner section which can be readily engaged and grasped between the finger tips to facilitate withdrawal of the pin.

The mechanical flattening operation to produce the flattened medial portion 11 may be accompanied by the crimping or bending operation of the spaced extensions 13 to produce the curved or wavy portions 12 in the legs or extensions 13.

In the embodiment of my invention shown in the illustrations, the entire surface of the stock of the hairpin is covered or coated with a preferably comparatively quick-drying composition 14 composed of very fine irregular metal particles, or finely ground crystalline quartz or silica particles, suspended or carried in a quick-drying liquid vehicle such as any suitable natural or colored lacquer. These metallic, quartz or silica particles must be reduced to a very fine and irregular size and preferably smaller in size than the cross-section of a human hair as comparatively diagrammatically illustrated in Figs. 7 and 8. Very fine irregular metallic particles with sharp edges or corners are preferable. The coating may be accomplished by dipping or spraying operation.

I have secured very favorable results by the use of fine metallic powders suspended in lacquers which are comparatively quick-drying and which metallic lacquers can be secured in various metallic colors or bronzes and which afford the production of my improved hairpins in shades and colors harmonizing or blending with various colors of hair; as for example, pale gold for blond hair, silver for gray hair, gun metal for iron gray hair, various bronzes for various brown hairs, copper bronzes for red hair and black metallic powder lacquers for black.

These metallic powder lacquers afford desirable colors and produce a surface texture of the desired frictional resistance and while the frictional quality afforded is sufficiently high to secure the desired resistance, the very sharp edges of the metal particles are sufficiently modified by the lacquer to prevent cutting or tearing of the hair.

In the embodiment of my invention illustrated in Fig. 9 the desired surface texture of the hairpin stock is attained by imparting to the metal stock 15 a twist along its longitudinal axis. The

stock of round or other cross-section is bodily twisted along its longitudinal axis to thereby distort the surface and produce a satin finish of ridge-like lines 16 of spiral form longitudinally of the stock. The illustration in Fig. 9 shows one form of this modification greatly enlarged.

I claim:

1. A hairpin including the surface of the body thereof substantially completely coated with a composition consisting of finely divided particles of inorganic matter of irregular shapes carried in a hardened fluid vehicle.
2. A hairpin having the surface of the body substantially completely coated with a composition consisting of minute particles of metal carried in and coated with a hardened lacquer.
3. A hairpin having the surface of the body substantially completely coated with a composition consisting of minute particles of quartz carried in and coated with a hardened lacquer.
4. A hairpin having the surface of the body thereof substantially completely coated with a composition consisting of finely divided particles of inorganic matter of irregular shapes carried in a hardened pigmented fluid vehicle.
5. A hairpin having the surface of the body substantially completely coated with a composition consisting of minute particles of metal carried in and coated with a hardened pigmented lacquer.
6. A hairpin having the surface of the body substantially completely coated with a composition consisting of finely divided particles of inorganic matter of irregular shapes carried in a hardened pigmented fluid vehicle.
7. A hairpin having the surface of the body thereof substantially completely coated with a composition consisting of finely divided irregular granular particles of matter supported in a hardened vehicle on said surface.

RAYMOND LARSON.
